UNITED STATES PATENT OFFICE

2,605,040

BAG CONSTRUCTION

Daniel Belcher, Minneapolis, Minn., assignor to
 Bemis Bro. Bag Co., Minneapolis, Minn., a corporation of Missouri

Application April 12, 1948, Serial No. 20,490

3 Claims. (Cl. 229—53)

1

My invention relates generally to the bag-making art and, more specifically, to the making of bags from material which is normally so flimsy or sleazy as to be incapable of cooperating with well-known bag closure mechanism to provide a proper closure therefor.

Cellophane is a typical example of such material. Cellophane and like sheet materials are ideally suited for the packaging of commodities because they have considerable tensile strength and yet are thin and transparent. However, in the mechanical packaging of goods in bags formed from such sleazy or flimsy materials, and more particularly in providing adequate closures by mechanical means for such bags, certain well-recognized problems have confronted the industry.

A conventional bag is initially formed into a tube from flat sheet material. Thereafter, the bottom of the bag is closed in any suitable manner—approximately one-quarter of the length of the tube being utilized for this purpose. Approximately two-thirds of this closed-bottom bag is utilized for the contents or fill and the remaining one-third, adjacent the open top, is utilized to provide an adequate top closure. Such top closures are made mechanically, an example of such mechanism and a method of closing such a bag being illustrated in Belcher Patents 1,868,686 and 1,989,471.

A single sheet of thin cellophane is so lacking in rigidity that it will collapse under the pressure of mechanical closure mechanism. This may also be true of two or more sheets or plies adhered together. It is in attempting to mechanically close bags formed from one or two sheets of cellophane (or any other material having similar characteristics) and after the contents or fill have been placed in the open-topped bag, that the particular problem with which we are here confronted arises. In other words, unless the unsupported approximately one-third of the bag projecting above the fill has considerable rigidity or body, it will collapse upon contact with the mechanical closure mechanism, thus rendering closure by mechanical means impossible. Therefore, in order to attain sufficient stiffness or rigidity for the upper one-third of the bag (one-quarter of the tube from which the bag is formed), the industry has found it necessary to make the entire bag from cellophane which is heavier than is normally required to carry the contents of the bag. This may be done, either by forming the bag from a single ply of cellophane of sufficient thickness to prevent collapse upon contact with mechanical top-closure mechanism or by form-

ing the bag from two or more thinner plies of cellophane, which in the aggregate have sufficient rigidity or stability to prevent collapse upon contact with mechanical top-closure mechanism.

5 However, in either event, the cost of producing such bags runs unnecessarily high, in view of the fact that three-quarters of the tube from which the bag is formed is formed from thicker material than is necessary.

10 The primary object of my invention is the provision of a bag, all but the approximate upper one-third or foldable top portion thereof being formed of light, sleazy, and inexpensive material of insufficient rigidity to cooperate with conventional bag closure mechanism—the upper one-third thereof being of such rigidity as to enable said closure mechanism to successfully operate thereon and therewith.

Another object of my invention is to materially 20 reduce the cost of producing bags from sleazy material without unduly impairing the quality of said bags.

The above and still further objects of my invention will become apparent from the following 25 detailed specification, appended claims, and attached drawings.

Referring to the drawings, wherein like characters indicate like parts throughout the several views:

30 Fig. 1 is a view in perspective of a non-gusseted bag having its upper or open end stiffened in accordance with my invention;

Fig. 2 is a view corresponding to Fig. 1, but showing a gusseted type of bag;

35 Fig. 3 is a view in perspective illustrating the position which the bag of Fig. 1 assumes when the contents are placed therein, but prior to providing a top closure;

Fig. 4 is a view corresponding to Fig. 3, but showing the bag in a partially closed condition;

40 Fig. 5 is a fragmentary perspective illustrating the bag of Fig. 1 in a totally closed and sealed condition;

Fig. 6 is a fragmentary view in elevation, some 45 parts broken away and some parts shown in section, illustrating a modification of the stiffening thereof; and

Fig. 7 is a view corresponding to Fig. 6, but showing a still further modification of the stiffening applied thereto.

Referring particularly to Figs. 1, 3, 4 and 5 of the drawings, the numeral 1 indicates, in its entirety, a bag having a tubular body 2 and having a closed bottom 3, which is formed from approximately the bottom one-quarter of the original

open-ended tube, from which the bag 1 is made.

It may be pointed out that no problem arises in the providing of an adequate bottom closure 3 by mechanical means in view of the fact that the tubular material from which the bag is formed is folded flat as indicated in Fig. 1, and is amply supported during the closure operation. Therefore, the thickness or rigidity of the material from which this portion of the tube is formed is of no particular consequence.

While bag 1 may be formed from one or more plies of material, as shown, it is formed of two plies of material, such as cellophane, and identified by the numerals 4 and 5. It will be observed that the fill portion of the bag 1, or that portion set aside for the contents, is approximately two-thirds of the height thereof. The limits of the fill portion are identified by the numerals 6-6 in Fig. 3. The remaining approximately one-third of the closed-bottom bag 1, adjacent the open upper end thereof, is utilized to provide an adequate top closure for said bag. The limits of the foldable upper portion of the tubular body are identified by the numeral 7-7 in Fig. 3.

When the contents or fill of the bag is placed therein, as indicated in Fig. 3, the tubular body 2 assumes a generally rectangular form. This is true whether the bag is of the type illustrated in Fig. 1, or of the type illustrated in Fig. 2. It should be here pointed out that the rigidity of the material from which the portion 6-6 of the tubular body 2 is formed is not of any particular importance because of the fact that the fill or contents of the bag support and prevent collapse of that section. Therefore, in bags constructed in accordance with my novel invention, the portion 6-6 may be and is formed from materials which are too light and sleazy to permit bag closure mechanism to properly operate thereupon.

Referring now to that portion of the bag representing approximately one-third of the length of the tubular body 2 above the fill portion 6-6, and identified by the numeral 7-7, it will be observed that this portion also assumes a generally rectangular cross-sectional shape when the fill or the contents have been placed in the tubular body 2; and I have found that while section 7-7 may be formed of material which will maintain itself erect when in such tubular form, nonetheless, it may not have sufficient rigidity to enable a closure to be made mechanically therewith. On the other hand, I have found, if the material forming the portion 7-7 is of, or has imparted thereto sufficient rigidity to prevent total collapse under the action of the mechanical closure mechanism, a mechanically-formed top closure may be successfully made therewith.

The portion 7-7, being initially identical (insofar as thickness of material, number of plies and the like is concerned) with the bottom 3 and the intermediate portion 6-6 of bag 1, will not withstand the forces exerted thereupon by mechanical bag closure mechanism; and I have found that sufficient rigidity to allow mechanical closure mechanism to successfully operate thereon, may be imparted thereto in several different but equally satisfactory ways. For instance, in the structures of Figs. 1 to 5 inclusive, this is accomplished by applying a stiffening adhesive,

in a broadcast manner and without regard to fold lines, between the plies 4 and 5. In the case of a one-ply bag, the reinforcing of portion 7-7 may be accomplished by applying a stiff drying ink or coloring agent to the entire surface thereof or to a sufficient portion of the area to create the desired result.

In Fig. 6, the stiffening agent has been applied to the portion 7-7 by means of diagonally criss-cross lines, whereas, in Fig. 7, the stiffening agent has been applied to the area 7-7 in parallel vertical lines. No regard in either instance is had to fold lines.

The bag of Fig. 2 differs from the bag of Figs. 1, 3, 4, and 5 only in that it is a so-called gusseted type. So far as this invention is concerned, the bag in Fig. 2 is treated as similar in all respects to the bag illustrated in Figs. 1, 3, 4, and 5 and the several parts thereof carry the same marks with prime marks added.

While I have shown several different methods of constructing bags in accordance with my invention, it should be understood that my invention should not be limited to any particular type of bag, to the type of material used, to the number of plies of material used, or to the particular manner of imparting rigidity to the foldable upper end portion of the bag, except as defined by the appended claims.

I claim:

1. A pre-formed collapsed bag having a tubular body open at one end and composed of flimsy transparent plastic material, the top foldable surface areas at the open end of the body being coated with a stiffening adhesive extending downwardly from the top edge to substantially one-third the length of the bag and terminating at points in a common plane defining the fold line in the formations of an end closure from said stiffened areas, said material rendering said bag self-sustaining in said top foldable areas, whereby to facilitate the automatic filling and closing of bags having flimsy wall structures.

2. A bag according to claim 1, wherein the stiffened areas are relatively narrow stripes of stiffening material extending inwardly from the open end of the tubular body to said common plane defining the top fold line.

3. A bag according to claim 1, wherein said tubular body is composed of superimposed plies of transparent flimsy plastic material, and said plies being adhered only inwardly from said open end to said common plane by said stiffening adhesive material.

DANIEL BELCHER.
